United States Patent Office.

SAMUEL B. B. NOLAN, OF NEW YORK, N. Y., ASSIGNOR TO JAMES COLEMAN AND WILLIAM BAXTER, OF SAME PLACE.

Letters Patent No. 96,947, dated November 16, 1869.

IMPROVEMENT IN PUMPS.

The Schedule referred to in these Letters Patent and making part of the same

To all whom it may concern:

Be it known that I, SAMUEL B. B. NOLAN, of the city, county, and State of New York, have invented a new and useful Improvement in Duplex Double-Siphon Force-Pump; and I do hereby declare that the following is a full, clear, and exact description thereof, which will enable others skilled in the art to make and use the same, reference being had to the accompanying drawing, forming part of this specification.

This invention relates to new and important improvements in force-pumps for raising and forcing water; and

The invention consists in the combination and arrangement of certain mechanical appliances and devices, applicable to either double or single-acting pumps, for supplying feed-water to steam-boilers and fire-engines, and for various other purposes, as will be hereinafter more fully described.

The accompanying plate of drawings represents a central vertical section of a pump constructed according to my invention.

Similar letters of reference indicate corresponding parts.

A and B represent a double cylinder, the parts being separated by the partition C.

D is the piston-rod, which works through a suitable stuffing-box in the end of the cylinder.

E E represent valve-pistons on the rod, one working in cylinder A, the other in cylinder B, as seen in the drawing.

F is the supply-pipe, which communicates with the water in the well or reservoir.

G and H represent the siphon-pipes, which connect the cylinder A B with the compressing-chamber I.

The latter is formed by and between the shell or cylinder R and the cone-shaped (inverted) receptacle S.

The vessel S is designed to be constantly full of water, so as to prevent the air from entering the pipe N. It is supported on the shell R by a perforated flange, and through the perforations therein the water flows on its passage through the pump.

I' denotes the chamber in the vessel S.

J is an oscillating gate-valve, which alternately opens and closes the siphon-pipes G H, as the pistons play back and forth in the cylinders.

K K represent flap-valves, which alternately open upward, to admit the flow of water into the cylinder.

L is the discharge-pipe.

The pipe is attached, by the coupling-nut M, to the top of the compressing-chamber pipe N.

In using the pump as a garden or hand fire-engine, (for which purpose it is admirably adapted,) a hose may be attached, instead of a rigid pipe.

The course of the water from the supply-pipe F is indicated by the arrows.

In this example of my invention, the pump is worked by means of the lever O, the fulcrum of which is on the bed-plate P, at q; but I do not confine myself to any particular method of driving the pump.

The operation of the pump will be readily understood from the drawing.

By this arrangement, a constant flow of water is secured, while, by the arrangement of the valves, the falling or loss of water in the pumps is prevented.

The advantages of this arrangement for the uses to which force-pumps are applied are many, and must be obvious to all.

Having thus described my invention,

I claim as new, and desire to secure by Letters Patent—

1. The combination of pipe N and chambers I I', as and for the purpose specified.

2. The arrangement of the siphon-pipes G and H, and the oscillating valve-gate J, in combination with a double-acting force-pump, substantially as described.

3. The combination of the double cylinder A B, pistons E E, siphon-pipes G H, valve J, chamber I, and pipe N, with the valves K K, when the same are arranged to operate substantially as and for the purposes described.

SAML. B. B. NOLAN.
